(57) **CLAIM**

The ornamental design for a shoe wedge training aid, as shown and described.

DESCRIPTION

FIG. 1 is a front perspective view of the shoe wedge training aid in accordance with the present invention;

FIG. 2 is a rear perspective view thereof;

FIG. 3 is a right side view thereof, the left side view being a mirror image;

FIG. 4 is a top plan view thereof;

FIG. 5 is a bottom plan view thereof;

FIG. 6 is rear elevational view thereof; and,

FIG. 7 is a front elevational view thereof.

The features shown in broken lines form no part of the claimed design.

1 Claim, 3 Drawing Sheets
